UNITED STATES PATENT OFFICE.

CHARLES VAN WINKLE, OF RUTHERFORD, NEW JERSEY.

DESIGN FOR A VEGETABLE-MASHER.

SPECIFICATION forming part of Design No. 30,067, dated January 24, 1899.

Application filed December 28, 1898. Serial No. 700,561. Term of patent 14 years.

To all whom it may concern:

Be it known that I, CHARLES VAN WINKLE, of Rutherford, in the county of Bergen and State of New Jersey, have invented a new and 5 original Design for a Vegetable - Masher, of which the following is a full, clear, and exact specification.

Reference is to be had to the accompanying drawing, forming a part of this specification, 10 in which the figure is a perspective view of a vegetable-masher showing my design.

The design in its entirety consists of an 15 open-mesh bottom A, from the edge of which rises an annular band or rim D, appearing suspended from spaced rods C, extending up-

wardly and terminating in a handle portion D, the end of one of the handle members being wound around the other members at the junction of the rods with the handle portion.

The leading feature of the design consists 20 of the open-mesh rimmed bottom and the rods terminating in a handle.

I claim—

The design for a vegetable-masher, as herein shown and described.

CHARLES VAN WINKLE.
